UNITED STATES PATENT OFFICE.

CLARENCE M. STOKES, OF NORRISTOWN, PENNSYLVANIA.

PIPE-COVERING.

1,137,432.

Specification of Letters Patent. Patented Apr. 27, 1915.

Application filed June 27, 1910. Serial No. 569,080.

To all whom it may concern:

Be it known that I, CLARENCE M. STOKES, a citizen of the United States, residing at Norristown, in the county of Montgomery and State of Pennsylvania, have invented a certain new and useful Improvement in Pipe-Coverings, of which the following is a specification.

My invention relates to a new and useful improvement in pipe coverings, and has for its object to construct a device of this character of a number of ribbons of suitable insulating material, said ribbons being spirally wound, one upon the other so that the uppermost ribbon always overlaps the joints of the ribbon beneath.

In accomplishing the above named objects I cut an insulating material such as wool or shoddy felt paper, known to the trade as deadening felt, into relatively long and narrow strips or ribbons. I then take a number of these ribbons and wind them spirally, one upon top of the other, using as many ribbons as necessary to produce the finished article of the desired thickness. Each outermost ribbon is so wound that it overlaps or covers the joints formed by the inner ribbon, thus preventing the radiation of heat which would occur if the joints were in alinement. In practice, any desired insulating material may be used, or a number of insulating materials may be combined, that is, the inner ribbon may be of asbestos, the next may be of wool felt, another of tar felt and so on, using any suitable insulating material, and if found desirable these ribbons may be corrugated so that when they are wound together air spaces will be formed which prevent the radiation of heat in a very effective manner.

With these ends in view, this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawings

forming a part of this specification, in which—

Figure 1 is a perspective view showing plain fabric used in the construction of the pipe; and Fig. 2, is a similar view, illustrating a modification.

In carrying out my invention as here embodied, A represents one of a number of ribbons of insulating material, which are spirally wound one upon the other forming layers until the desired thickness of the covering is obtained, each succeeding ribbon covering or overlapping the joints B formed by the preceding ribbon. In winding these ribbons an adhesive material, such as corn starch, silicate of soda or a composition of rubber, is placed between each pair of ribbons so that they always remain securely in position. The ribbons from which the covering is made are of deadening felt, (a paper made from wool or shoddy) asbestos, tar felt or any other suitable insulating material, and when making a covering all of the ribbons may be of any one of the insulating materials or two or more different insulating materials may be used.

In Fig. 2, I have shown the several layers of fabric corrugated longitudinally to form air spaces when the several layers are assembled, and to increase the insulating properties of the pipe.

To place the covering upon a pipe, it is cut or split longitudinally, then placed about the pipe and covered with canvas or a sheeting jacket pasted down to form a finish and also to hold the covering in place upon the pipe. This sheeting jacket is used upon all pipe coverings of the present day, and it is therefore thought unnecessary to illustrate or describe the same in detail.

Having thus fully described my invention, what I claim as new and useful, is—

1. A pipe covering consisting of a spirally wound strip of asbestos, an adhesive applied to the outer surface of said spirally wound strip and a second strip of deadening felt wound about the first named strip and adhesive, and so disposed as to overlap the joint formed by the spiral winding of the first named strip, said covering being split

2
longitudinally as and for the purpose set forth.

2. A pipe covering consisting of a spirally wound corrugated strip of insulating material, a second corrugated strip of insulating material spirally wound about the first named strip and so disposed as to overlap the joint formed by the winding of the first named strip, and an adhesive disposed between said strips for securing them together,

said covering being split longitudinally for the purpose described.

In testimony whereof, I have hereunto affixed my signature in the presence of two subscribing witnesses.

CLARENCE M. STOKES.
